UNITED STATES PATENT OFFICE.

JOHN CORTLANDT SKINNER, OF FRESNO, CALIFORNIA.

REINFORCED DISPLAY-RECEPACLE.

1,036,358.

Specification of Letters Patent. Patented Aug. 20, 1912.

Application filed November 22, 1911. Serial No. 661,774.

To all whom it may concern.:

Be it known that I, JOHN C. SKINNER, a citizen of the United States, residing at Fresno, in the county of Fresno and State of California, have invented certain new and useful Improvements in Reinforced Display-Receptacles, of which the following is a specification, reference being had therein to the accompanying drawing.

10 This invention relates to display and vending receptacles such as are used in grocery stores and the like for containing groceries and other articles to be sold.

One object of the invention is to provide 15 a device of the character described wherein a plurality of receptacles may be piled one upon the other and access may be had to the contents of each without disturbing any of the remaining receptacles.

20 A second object of the invention is to provide a display receptacle having a portion of the front forming a door of the drop-down type, said door being likewise adapted for the display of the goods to be vended in 25 a neat and orderly manner.

A third object of the invention is to provide 30 a door of this character with side wings to prevent spilling of the goods from the receptacle, said side wings being housed in suitable housings to prevent injury to the 35 goods contained by the edges of the side wings as they move backward toward the closing of the door.

With the above and other objects in view 40 the invention consists in general of certain novel details of construction, and combinations and arrangements of parts as will be hereinafter fully described, illustrated in the accompanying drawings, and specifically claimed.

In the accompanying drawings, like characters of reference indicate like parts in the several views, and Figure 1 is a perspective view of the improved receptacle with the lid 45 and the door both opened. Fig. 2 is a transverse median section through the invention. Fig. 3 is a section on the line 3—3, Fig. 2. Fig. 4 is a section on the line 4—4, Fig. 3. Fig. 5, is a section on the line 5—5, Fig. 3, 50 the section being partly broken away. Fig. 6 is a detail view of the rear edge of the upper lid or filling lid of the invention.

The invention consists of a casing 10 which is open at the top as indicated at 11 55 and on this top portion there is fitted a lid 12. This lid has its hinged edge strength-

ened by being widened as at 13 so that the lid tapers from back to front and surrounding the edge thereof is a reinforcing wire which has the edge beaded thereover as at 14. This bead has the edge portion cut away at certain points as at 15 so that hinges 16 may be secured around the wire left open and attach the lid to the rear of the box. The lower part of the front of the box is 65 also cut away as at 17 while the upper part of this box is slotted along the dotted lines 18 and 19 in Fig. 1 so that the portions left may be bent to reinforce the box front. The upper portion above the upper slit 18 is 70 doubled back upon itself as at 20 and the lower portion below the lower slit 18 is doubled up as at 21, thence outward and upward as at 22, and back and down again as at 23, and terminates in connection with a 75 vertical partition 24, spaced from the front, by means of a floor 25. Each of the side portions between the slits 18 is bent backward as at 26, thence forward again in spaced relation as at 27, thence backward as 80 at 28, and thence rearward as at 29, the free edge of the portion 29 being soldered to the partition 24 and to the side walls of the casing 10. To the rear of the partition 24 there is provided a platform or partition 30 85 which rests upon the edges of vertical housing walls 31 at each side and in spaced relation to the sides of the casing 10.

Extending between the sides of the casing 10 is a rod 32 whereon are spring hinges 33 90 which serve to connect the door 34 to the rod 32. This door is cut away centrally and is provided with rearwardly bent portions 35 and similar parallel portions 36 which form species of U-shaped clips for the reception of glass 37. In spaced relation to the glass 37 the door is provided with a partition 38 which is carried by wings 39 of segmental form. These wings have their front edges secured to the side edges of the door and slidable between the housing walls 31 in the side walls of the receptacle. From the bottom of the partition 38 extends a floor 40 which is upwardly and then downwardly bent as at 41 to keep the bottom 100 edge of the glass 37 from sliding rearwardly. Below the floor 40 is a guide plate 42 so that when the door is opened the contents of the receptacle 10 can be drawn out without bruising the same against the sharp 105 edge.

The lid and casing and the door and cas-

ing are provided with suitable forms of latch as indicated at 43 and it will be plain that the upper portion of the front of the casing is likewise provided with suitable 5 glass 44 closing in the opening made in this upper portion. The goods to be displayed can be placed both in the compartment formed between the partition 24 and the upper part of the front and in the com- 10 part formed between the partition 38 and the door so that these goods can be seen through the glass in both places, thus making an attractive display. When it is desired to fill the receptacles the lid 12 may 15 be opened and goods placed therein, certain of the goods being arranged in an orderly manner in the compartments just referred to. When the lid of a receptacle is closed other receptacles may be stocked and by 20 means of the door at the lower portion of the front this receptacle can be emptied or partly emptied at any time without disturbing those superposed thereon.

It will be obvious that the door may be 25 placed either at the front or the side in which latter case necessary modifications will have to be made in the display device.

There has thus been provided a simple

and efficient device of the kind described and for the purpose specified.

Having thus described the invention, what is claimed as new, is:

In a display receptacle, a casing provided with a shallow compartment having a glass front, a lid attached to the body of the casing and said compartment, a door provided with segmental side wings and pivoted along its lower edge closing the lower portion of one side of said casing, said door carrying a shallow compartment, said door being provided with a glass front and a beveled lower end, said lower end being beveled to permit ready withdrawal of the contents of the receptacle, housing for said wings, a plate behind the first-mentioned shallow compartment and resting on said housings, constituting a retaining plate, said lid being provided around its rim with a reinforcing ring, and guards for retaining said glasses in said compartments.

In testimony whereof I hereunto affix my signature in presence of two witnesses.

JOHN CORTLAND SKINNER.
